BRAKE

Edwin W. Bereit, Mentor, Ohio, assignor to The
Cleveland Crane & Engineering Company,
Wickliffe, Ohio, a corporation of Ohio

Application January 9, 1930, Serial No. 419,561

10 Claims. (Cl. 188—62)

This invention relates to a braking device which has particular application in connection with overhead carriers, although it is to be understood that its use is not to be limited thereto.

5 An object of the present invention is to provide a brake which will normally tend to stop a load brought into engagement therewith, and which may be manually rendered ineffective, to thereby release the braked load or permit the load

10 to travel past the brake without braking operation.

Another object of the invention is to provide a brake disposed in the path of movement of the load and normally positioned for engagement therewith, to thereby bring the load to a stop gradually against increasing resistance.

A further object of the invention is to provide a positive stop for the load in the event that the weight of the load is in excess of the braking 20 resistance of the brake.

A further object of the invention is to provide a device of the character described, which is simple in construction, efficient in operation and inexpensive to manufacture.

25 With the objects above indicated and other objects hereinafter explained in view, my invention consists in the construction and combination of elements hereinafter described and claimed.

30 Referring to the drawing:

Figure 1 is a side elevational view of an apparatus embodying the present invention.

Figure 2 is a horizontal transverse view taken along line 2—2 of Figure 1.

35 Figure 3 is an end elevational view of the same.

In the drawing an I-beam 10 is illustrated, which forms a part of the usual superstructure provided in connection with installations of this particular character, and which is preferably

40 supported in any suitable manner from the roof or other portions of the building. This I-beam 10 is disposed above a monorail track 11, forming part of the overhead conveyor system, and which track is suspended from the beam 10 by a plurality of hanger rods 12.

A carrier, generally indicated at 13, is adapted to convey the load along the overhead system to any desired location, and comprises, in the present instance, an I-beam, 14, which is suspended 50 beneath the monorail track 11 and adapted to move therealong through the medium of a front carrier 15 and a rear carrier 16 of the usual type, comprising wheels disposed on opposite sides of the monorail track 11 and adapted to travel along the laterally extending flanges thereof. The rear

carrier 16 is provided with a swivel 17, to afford substantially universal movement, so as to permit the carrier to pass around curves and the like.

While the type of carrier herein illustrated is adapted for manual operation, it should be understood that the braking apparatus about to be described in connection therewith is as readily effective with other types of carriers, and that the invention is not to be limited thereto.

In connection with conveyor systems of various types it is desirable to be able to stop the loads carried thereby at predetermined locations for various reasons, and it is one of the important features of the present invention to provide an efficient braking mechanism which will fulfill this purpose. Such a mechanism has particular application in connection with overhead conveyor systems which extend through bakers and similar operating rooms, and it is important that the carriers be brought to a stop within the bakers for a predetermined period of time. This condition is only one of many, and it is to be understood that this invention is not to be limited to this particular use.

A pair of longitudinally extending angles 18 are disposed upon opposite sides of the I-beam 14 of the carrier 13, which have their upper legs extending inwardly in substantially the same plane as the upper flange of the I-beam 14, as shown in Figure 3. These angles 18 extend at a slight inclination in the direction of travel of the carrier and have their opposite ends depending, as indicated at 18', for a purpose to be later described. The angles 18 act as brake shoes in the braking operation and cooperate with the underextended surfaces of channel cross bars 19, secured to the upper flange of the I-beam 14 at the front and rear portions, respectively, as shown in Figure 1.

The angles 18 are connected by a suitable mechanism which will be hereinafter described, to cause them to move in a vertical plane in unison, and are so positioned that they will normally engage the undersurfaces of the channel cross bars 19 to cause braking action therebetween and tend to stop the travel of the load. Due to the fact that these angles 18 are inclined slightly in the direction of the travel of the load, the braking action or frictional resistance between the angles 18 and the channel cross bars 19 is increased, and because of the rigid connection between the I-beam 14 and the carriers 15 and 16, there is a tendency to relieve the load from the wheels of the carriers 15 and 16 and to support the load upon the angles 18. In the event

that the angles 18 were not capable of stopping an exceptionally heavily loaded carrier a pair of stops 20 are secured to the inwardly extending legs of the angles 18 and are disposed in the 5 path of movement of the channel cross-bars 19, so as to positively stop the load under such conditions.

Suitable linkage is provided between the I-beam 10 of the superstructure and the angles 18, 10 which linkage is indicated by 21 and 22, respectively, the linkage 21 being attached to the rear portions of the angles 18, while the linkage 22 is attached to the forward portions of the angles 18, and inasmuch as these linkages are identical in construction and operation it is believed 15 that the description and operation of the linkage 21 will suffice.

A pair of links 23 have their lower ends pivotally connected at 24 to the depending legs, 20 respectively, of the angles 18, while their upper ends are pivotally connected to a transversely extending rod 25. A pair of links 26 have their lower ends pivotally connected to the rod 25, while their upper ends are pivoted at 27 to a 25 cross-bar 28 preferably formed integral with an attaching plate 29. This attaching plate 29 is attached by means of bolts, or other suitable means, to the lower flange of the I-beam 10, and may have disposed therebetween shims 30, for 30 the purpose of obtaining the desired inclination of the angles 18. A pair of links 31 have their lower ends pivotally connected at 24 to the depending legs of the angles 18, while their upper ends are pivoted to a transverse extending rod 32. A pair of links 33 have their lower ends 35 pivotally connected to the transversely extending bar 32, while their upper ends are pivotally connected at 34 to a transversely extending member 35 formed integral with an attaching plate 36. This attaching plate 36 may be attached to 40 the lower flange of the I-beam 10 by bolts or other suitable means and also being spaced therefrom by shims 37. A pair of links 38 have their outer ends pivotally connected to the transverse rod 32, while their outer ends have attached 45 thereto a counterweight 39. A pair of links 40 have their outer ends pivotally connected to the transverse rod 25, while their outer ends have attached thereto a counter-weight 41. A transverse rod 42 connects the pairs of links 38 and 50 40 at a point substantially midway between the transverse rod 25 and the transverse rod 32 and provides a suitable pivot about which these links 55 may move. It will, therefore, be seen that when an upward pull is exerted upon the transverse rod 42 the linkage mechanism is moved into the position indicated by dotted lines in Figure 1, and such movement causes a downward movement of the angle members 18. This downward movement of the angle members 18 causes them 60 to be disengaged from the channel cross bars 19 a sufficient extent to permit the carrier to be moved without any braking action, and additionally over the positive stops 20.

65 A pull chain 43 extends over a sheave 44, and has provided at one end a handle 45, which is adapted to be pulled downwardly by an operator to move the linkage into the position indicated by dotted lines in Figure 1, to thereby release the 70 braking action upon the carrier.

The opposite end of the pull chain 43 has connected thereto a chain 46, which passes over a double sheave 45 supported by the beam 10, and is connected to the transverse rod 42, while a second chain 46 is connected to the pull chain 43

and passes over the double sheave 45 and a single sheave 47, suitably supported by the beam 10, and which has its opposite end connected to the transverse rod 42 of the linkage mechanism 22. It will, therefore, be readily understood that when the operator pulls upon the pull chain 43 both of the linkage mechanisms 21 and 22 operate in unison, so as to lower the angles 18 uniformly.

Tie bars 48 are provided for reinforcing the angles 18 and are disposed on opposite sides of the 10 angles 18, as shown in Fig. 3. The lower ends of the tie bars 48 are pivotally connected at 49 to the end portions of the angle bars, while the upper ends are pivotally connected to one of the cross-bars 28, as shown in Fig. 1.

In the operation of the device the loaded carrier travels over the monorail track 11 towards the left, as viewed in Figure 1. The channel cross-bars 19 pass over the forward ends of the angles 18, and gradually contact with the inwardly extending legs of the angles 18. The friction created by the engagement between these members resists the travel of the loaded carrier and tends to stop the same. This resistance is gradually increased, due to the slight inclination of the angles 18 in the direction of the travel of the carrier. If it is desired to urge the loaded carrier slightly forward the pull chain 43 may be operated by pulling the handle 45, which thus operates the linkage mechanisms 21 and 22, and thereby causes the angles 18 to be moved downwardly until they are out of engagement with the channel cross-bars 19. If it is desired to have the carrier move completely beyond the braking mechanism a downward pull is exerted on the handle 45 until the angles 18 are in their lower position, as indicated in dotted lines in Figure 1, in which event the channel cross-bars 19 may readily pass above the positive stops 20.

While I have described the preferred embodiment of the invention, it is to be understood that I am not to be limited thereto, as changes and modifications may be resorted to without departing from the spirit of the invention, as defined in the appended claims.

Having thus described my invention what I claim is:

1. In an apparatus of the character described, a load supporting member adapted to travel along a predetermined path, braking means mounted independently of said member and normally adapted to engage the latter at a point in its travel to gradually bring said member to a stop, means mounted upon said braking means and adapted for engagement with said supporting member for positively stopping the latter independently of the action of said braking means, and means operatively connected with said braking means for moving the latter to inoperative position.

2. In an apparatus of the character described, a track, a carrier adapted to travel along said track, braking means disposed at a predetermined point along said track and normally adapted to cooperate with said carrier to gradually bring the latter to a stop, means mounted upon said braking means and adapted for engagement with said carrier for positively stopping said carrier due to failure of said braking means, and means operatively connected with said braking means for moving the latter to inoperative position.

3. In an apparatus of the character described, an overhead track, a load supporting member disposed beneath said track, wheeled carriers connected to said load supporting member and

adapted to traverse said track, braking means along said track, means for raising said braking means to engage with said load supporting member to bring the latter to a stop, and means for lowering said braking means into a position out of engagement with said load supporting member.

4. In an apparatus of the character described, an overhead track, a load supporting member disposed beneath said track, wheeled carriers connected to said load supporting member and adapted to traverse said track, and a brake member normally in the path of movement of said load supporting member and disposed beneath said track, said brake member being movable bodily in a vertical plane to engage with said load supporting member to bring the latter to a stop.

5. In an apparatus of the character described, an overhead track, a load supporting member disposed beneath said track, wheeled carriers connected to said load supporting member and adapted to traverse said track, spaced members disposed beneath and extending substantially parallel with said track, and transversely extending means connected to said load supporting member and adapted to engage said spaced members to bring said load supporting member to a stop.

6. In an apparatus of the character described, an overhead track, a load supporting member disposed beneath said track, wheeled carriers connected to said load supporting member and adapted to traverse said track, a brake member positioned along said track and adapted to engage said load supporting member to bring the latter to a stop, and weighted means acting upon said brake member.

7. In an apparatus of the character described, an overhead track, a load supporting member disposed beneath said track, wheeled carriers connected to said load supporting member and adapted to traverse said track, a bodily movable braking member positioned along said track and adapted to normally engage said load receiving member to retard its movement along said track,

and interengaging means between said load supporting member and said brake member for positively stopping said load supporting member.

8. In an apparatus of the character described, an overhead track, a load supporting member disposed beneath said track, wheel carriers connected to said load supporting member and adapted to traverse said track, brake bars extending longitudinally of said track and connected in spaced relation, said bars being normally positioned in the path of movement of said load supporting member to thereby cause the latter to be gradually stopped, means supporting said bars for vertical movement bodily, and means for moving said bars.

9. In apparatus of the character described the combination of an overhead track, a brake member having an upwardly inclined engaging surface extending longitudinally of said track and supported adjacent the same, a carrier including load supporting means on said track adapted to travel therealong, the carrier having a portion thereof adapted to engage and ride up on the upwardly inclined surface of said brake member whereby part or all of the weight of the load carried thereby is transferred to said brake member and the carrier brought to a stop, and means for lowering said brake member to release the carrier.

10. In an apparatus of the character described the combination of an overhead track, a carrier including load supporting means on said track adapted to travel thereon, a brake member extending longitudinally of said track positioned adjacent the same and adapted to engage the carrier and lift the load supporting means to bring the carrier to a stop, toggle links operatively connected to said brake member for suspending the same adjacent said track, means for moving said toggle links whereby said brake member is raised or lowered with reference to said track, and means for limiting the movement of said brake member longitudinally of the track.
